PAPER ROLL HOLDER

Lonnie O. Cantrell, Whittier, Calif.

Application April 3, 1951, Serial No. 219,029

3 Claims. (Cl. 242—55.2)

1

This invention relates to paper roll holders and more particularly to a holder for holding rolls of toilet paper and dispensing the paper therefrom.

It is among the objects of the invention to provide an improved paper roll holder in which the roll engaging spindle is supported at one end only leaving the other end free for the easy replacement of paper rolls on the holder; in which the spindle is provided with resilient arms on which the paper rolls are mounted and firmly retained and friction means are provided between the spindle and its support for retarding rotation of a paper roll mounted on the spindle; and which is simple, strong and durable in construction, economical to manufacture and neat and attractive in appearance.

Other objects and advantages will become apparent from a consideration of the following description and the appended claims in conjunction with the accompanying drawing wherein:

Figure 1 is a top plan view of a paper roll holder illustrative of the invention;

Figure 2 is a front elevational view of the holder with a paper roll mounted thereon, portions of the paper roll and the holder being broken away and shown in cross section to better illustrate the construction of the holder;

Figure 3 is a fragmentary end elevational view looking at the right-hand end of the holder and paper roll as illustrated in Figure 2; and

Figure 4 is a fragmentary end elevational view looking at the other end of the paper roll and holder.

With continued reference to the drawing, the holder comprises an angle bracket 10 having flat legs 11 and 12 disposed substantially at right angles to each other with the leg 12 materially longer than the leg 11 and tapering in width in a direction away from its connection with the leg 11. The leg 11 is provided with apertures spaced apart transversely thereof to receive suitable fasteners, such as the screws 13, for securing the bracket to a supporting structure, such as the wall 14, with the leg 11 substantially vertically disposed and the leg 12 projecting outwardly from the wall substantially perpendicular thereto.

The leg 12 is provided near its distal end with an aperture 15 and an elongated pin 16 is received in this aperture and has at one end a head 17 bearing against the side of the leg 12 disposed outwardly of the leg 11. This pin has a length substantially equal to the length of a roll of toilet paper, as indicated at 18, and a sleeve 19

2

somewhat shorter than the pin 16 has an axially extending bore which receives the pin. This sleeve bears at one end against the side of the bracket leg 12 remote from the head 17 of the pin and the pin and sleeve are disposed substantially horizontally and substantially parallel to the supporting wall when the bracket 10 is properly mounted in operative position on the wall.

A substantially U-shaped spring structure 20 has an intermediate or bight portion 21 provided with a central aperture 22 which receives the pin 16 at the end of the sleeve 19 remote from the bracket leg 12 and a pair of spring arms 23 and 24 extending along the sleeve 19 in spaced relationship thereto from respectively opposite sides of the intermediate portion 21. The intermediate portion 21 has a length slightly less than the diameter of the tubular core 25 of the paper roll 18 and the spring arms have a length slightly less than the length of the sleeve 19, so that the ends of these spring arms adjacent the bracket leg 12 are spaced from the adjacent surface of this bracket leg, as is particularly illustrated in Figure 2. At their ends remote from the intermediate or bight portion 21 the arms 23 and 24 are provided with outwardly projecting stop formations 26 and 27 which engage the corresponding end of a paper roll mounted on the spring structure and limit movement of the paper roll toward the bracket leg 12. It will be noted that the bracket leg 12 has a length somewhat greater than the radial dimension of a full paper roll, so that when a paper roll is mounted on the spring structure 18 it will be spaced from the surface of the wall 14.

An abutment washer 28 is secured on the pin 16 at the end of the pin remote from the head 17 by suitable means, such as the cotter key 29 extending through a transverse aperture in the pin near the corresponding end of the latter and bearing against the outer side of the washer 28 and a coiled compression spring 30 surrounds the pin 16 between the abutment washer 28 and the intermediate portion 21 of the spring structure 20 forcing the end of the sleeve 19 adjacent the bracket leg 12 against this bracket arm and the intermediate portion 21 of the spring structure against the adjacent end of the sleeve to provide a braking action on the spring structure for retarding rotation of a paper roll mounted thereon.

The pin 16, the sleeve 19 and the spring structure 20 together provide a roll receiving unit and the paper roll is mounted on this unit by forcing the tubular core of the paper roll 25 onto the

unit from the end of the pin carrying the abutment washer 28. When there is no paper roll on the supporting unit the arms 23 and 24 of the spring structure diverge relative to each other in a direction away from the intermediate spring portion 21, as indicated in Figure 1, but, when a paper roll is mounted on the unit these arms are brought together by the tubular core 25 until they are substantially parallel and both contact the inner surface of the paper core throughout substantially the entire length of the spring arms.

This support greatly facilitates the placing of full paper rolls on the support and the removal of the empty core tubes therefrom as it is necessary only to force the rolls on from the free end of the roll supporting unit and to pull the empty tubes off from this end of the unit. The spring structure holds the paper roll firmly on the holder until the roll is entirely dispensed and the entire device is simple in construction and economical to manufacture, and easy to mount on a supporting wall or other supporting structure.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A paper roll holder comprising an angle bracket having one leg apertured for attachment to a wall and its other leg provided with an aperture adjacent the distal end thereof, a pin received in the aperture in said other leg and having at one end a head bearing against one side of said other leg, a sleeve receiving said pin and bearing at one end against the other side of said other leg, a spring structure including an apertured intermediate portion receiving said pin and bearing against the other end of said sleeve and arms spaced from and extending along said sleeve from respectively opposite sides of said intermediate portion, an abutment washer secured on said pin at the other end of the latter, and a compression spring surrounding said pin between said abutment washer and the intermediate portion of said spring structure compressing said sleeve between the intermediate portion of said spring structure and said other bracket leg to provide a braking action on said spring structure.

2. A paper roll holder comprising an angle bracket having one leg apertured for attachment to a wall and its other leg provided with an aperture adjacent the distal end thereof, a pin received in the aperture in said other leg and having at one end a head bearing against one side

of said other leg, a sleeve receiving said pin and bearing at one end against the other side of said other leg, a spring structure including an apertured intermediate portion receiving said pin and bearing against the other end of said sleeve and arms spaced from and extending along said sleeve from respectively opposite sides of said intermediate portion, an abutment washer secured on said pin at the other end of the latter, and a compression spring surrounding said pin between said abutment washer and the intermediate portion of said spring structure compressing said sleeve between the intermediate portion of said spring structure and said other bracket leg to provide a braking action on said spring structure, said other bracket leg having a length materially greater than the length of said one leg and greater than the radial dimension of a paper roll to be mounted on said holder so that a roll mounted on said holder will be spaced from a bracket supporting wall.
